US00D756432S

(12) **United States Design Patent**
Wright et al.

(10) **Patent No.:** **US D756,432 S**
(45) **Date of Patent:** **** May 17, 2016**

(54) **CONTACT LENS**

(71) Applicant: **Johnson & Johnson Vision Care, Inc.**,
Jacksonville, FL (US)

(72) Inventors: **Dawn D. Wright**, St. Augustine, FL
(US); **Jeffrey H. Roffman**, St. Johns, FL
(US); **Angie Bowers**, Jacksonville, FL
(US)

(73) Assignee: **Johnson & Johnson Vision Care, Inc.**,
Jacksonville, FL (US)

(**) Term: **14 Years**

(21) Appl. No.: **29/517,257**

(22) Filed: **Feb. 11, 2015**

(51) LOC (10) Cl. **16-06**

(52) U.S. Cl.
USPC **D16/101**
